DESIGN FOR A TOY RABBIT

Martin Berger, New York, N. Y.

Application March 23, 1946, Serial No. 127,857

Term of patent 7 years

(Cl. D34—2)

To all whom it may concern:

Be it known that I, Martin Berger, a citizen of the United States of America and resident of New York, county and State of New York, have invented a new, original, and ornamental Design for a Toy Rabbit, of which the following is a specification, reference being had to the accompanying drawing, forming a part thereof, in which

Fig. 1 is a side view of a toy rabbit embodying my new design.

Fig. 2 is a top view of the toy rabbit shown in Fig. 1 and

Fig. 3 is a back view of the toy rabbit.

I claim:

The ornamental design for a toy rabbit, as shown.

MARTIN BERGER.
